CLOCK SYNCHRONIZING APPARATUS

Raymond H. Barrows, Johnson City, N. Y., assignor to International Business Machines Corporation, New York, N. Y., a corporation of New York

Application November 23, 1949, Serial No. 129,017

1 Claim. (Cl. 58—34)

1

This invention relates to apparatus for synchronizing clocks, and in particular, to apparatus wherein a master clock having an auxiliary spring-type motor and conventional escapement mechanism is controlled from a remote point by an electrical impulse to come into synchronization with another master clock from which impulses originate.

Ordinarily clock systems comprised of master clocks and so-called secondary clocks, which are controlled by the master clock, are dependent for originating corrections of time upon a setting of the master clock whereupon by devious means all of the secondary clocks are caused to fall into synchronization, such synchronizing being carried out at predetermined periods of time. One such system is explained and illustrated in U. S. Patent 1,878,931 to Larrabee. In some time systems the master clock may be spring driven, in others an electric synchronous motor may provide the drive, and in still others a combination of the two is used for initiating the driving of the master clock. An example of the last-mentioned type of master clock driving mechanism is shown in U. S. Patent 2,424,119 to Rast. A further application of a master clock in a time system such as has been previously referred to is shown in a co-pending application, Serial No. 990 filed January 7, 1948, by Johnson and Geiger.

As explained in the co-pending application referred to above, it is obvious that in the case of an electrical power failure the synchronous motor, which normally provides power for driving the master clock mechanism, is brought to rest whereupon a cooperating spring motor takes over the drive and operates until the synchronous motor is again restored to its intended function. In some time systems two or more master clocks, sometimes referred to as slave master clocks, are controlled by a single master clock of exceedingly high accuracy. In these systems the so-called slave master clocks each control a plurality of secondary clocks and may themselves be corrected periodically from a single supervisory master clock controlling all of the satellite time systems. It is to such time-controlling devices that the present invention is particularly adapted.

The principal object of this invention is to provide a simple and effective means for correcting clocks having spring driven motors by means of periodic electrical impulses.

Other objects of the invention will be pointed out in the following description and claims and

2

illustrated in the accompanying drawings, which disclose, by way of examples, the principle of the invention and the best mode, which has been contemplated, of applying that principle.

In Fig. 1 of the drawings a partial view of a clock mechanism is shown adapted to embody the present invention. The section of the clock shown in the drawing of Fig. 1 represents substantially the clock mechanism referred to in the co-pending application discussed above, as indicated by the corresponding reference characters. It is to be understood, however, that the present invention may be embodied in any spring driven clock having an escapement similar to that shown in the drawings.

Fig. 2 of the drawings is a detail view illustrating the precise manner of operation of the invention.

Now referring to Fig. 1 of the drawings a mounting plate 19 is arranged to be fastened in an appropriate manner to a face plate 20 (see Figures 1 and 2, application Serial No. 990, January 7, 1948), so as to provide a support for a yoke 13 of an electromagnet 12. The electromagnet 12 is positioned above a balance wheel 78 in such a manner that an iron slug 11 mounted in the periphery of the balance wheel 78 is positioned radially at approximately 120 degrees from the pole tip 12 of the magnet when the balance wheel 78 is at rest. Normally when the spring motor is driving the mechanism the balance wheel 78 oscillates upon a shaft 10 regulated by a spring 82 under the control of a regulating arm 182 having a bifurcated end 184 which straddles a regulating pin (not shown). It is to be understood that any conventional escapement mechanism may be employed for driving the balance wheel 78; however, for purposes of clarification the marine escapement mechanism shown in the copending application of reference 40 may be considered most suitable. In this connection a small gear 86 mounted upon a seconds shaft 84, which is journaled between the front plate 20 and a rear plate 22, meshes with a large gear 62, which is driven by the spring motor, in such a way that shaft 84 turns at a rate of 1 R. P. M. A cam 14 is also mounted on the shaft 84 to rotate with the gear 86. A pair of contact straps 17 and 18, respectively, are mounted in an insulated plug 21 which is supported between the front and rear plates 20 and 22, respectively. Contacts 16 are provided on the ends of the straps 17 and 18 and a bearing member 15 is provided on the strap 18 to cooperate with the cam 14 so that as shaft 84 revolves the

contacts 16 will be made and broken for predetermined periods.

In operation the clock mechanism embodying the present invention is given sufficient potential energy by winding its main spring to drive the gear 62 and operate the balance wheel 78 thereby rotating the shaft 84 at a predetermined rate of one revolution per minute. The regulating arm 182 is then adjusted so that the balance wheel 78 oscillates at a higher rate than is necessary to cause the clock mechanism to keep correct time; i. e., shaft 84 actually turns at a rate greater than 1 R. P. M., consequently the clock mechanism will gain time at a rate depending upon the advancement of the regulating arm 182. At regular predetermined intervals electrical impulses of predetermined duration are supplied from a suitable electrical source for energizing the electromagnet 12 which through its pole tip 12a (Fig. 2) will attract the slug 11 thereby stalling the balance wheel 78; consequently, as actual time progresses, the clock mechanism will remain inoperative for the duration of each electrical impulse due to the balance wheel 78 being held stationary, and a corresponding correction in time will be made to compensate for the time normally gained.

One manner in which the above time correcting operation can be carried out is by arranging the member 15 and the cam 14 so that contacts 16 will be closed for the first 210 degrees of each revolution of the shaft 84 (corresponding in time to approximately the first 35 seconds of each minute) and opened for the remaining 150 degrees of each revolution of the shaft 84 (corresponding in time to approximately the last 25 seconds of each minute). The clock movement is then regulated by means of the fork 182 to run at a "fast" rate so that it gains approximately one quarter of a second per minute, and a source for providing electrical impulses is connected to the magnet 12, the contacts 16 being connected in series therewith. Since contacts 16 are closed from the zero or 60 seconds position to the 35 seconds position, an electrical impulse during this period will energize the magnet 12, which will therefore stop and retain the balance wheel 78 due to the magnetic attraction of the slug 11 and the pole tip 12a of magnet 12. During the period of rotation of shaft 84 from the 35 seconds position to the zero or 60 seconds position the contacts 16 will be open and the magnet 12 can not be energized.

Let it be assumed that an electrical impulse of 2 seconds duration is delivered to the magnet 12 via the series contacts 16 beginning the 58th second of each minute, and that such impulses are supplied regularly by a master clock such as disclosed in U. S. Patent 1,878,931. Also assume that the mechanism shown in Fig. 1 of the drawings is incorporated into a slave master clock having a spring motor drive, and that the clock is on time. Consequently when the 2 second impulse occurs, the shaft 84 of the slave clock will be at a position corresponding to the 58th second and contacts 16 will be open so that the magnet 12 is not energized and no time correction is made. If the slave master clock is 1 second fast, for example, the shaft 84 will be at a position corresponding to the 59th second when the 2 second impulse arrives (at the 58th second, actual correct time), and the contacts 16 will be open. However, the contacts 16 will close when shaft 84 revolves to a position corresponding to the 60th second, and since the electrical impulse at that time (one second later) has a remaining

duration of 1 second, the magnet 12 will be energized to attract the slug 11 in the balance wheel 78, halting its oscillations for 1 second, the slave master clock will lose 1 second in time thereby being corrected to indicate the correct time. Similarly a full correction of the slave master clock is made when it is 2 seconds fast.

When the slave master clock is more than 2 seconds fast a correction will be made of the order of 2 seconds each minute until correct time is again indicated by the slave master clock. With the arrangement of cam 14 and member 15, described above, corrections up to 37 seconds "fast" in the slave master clock can be compensated. It is obvious that no correction can be effected electrically if the slave master clock is "slow," except by regulating the arm 182 to cause the spring motor under control of the balance wheel 78 to drive shaft 84 at a higher rate. For most practical purposes, however, a correction of a fraction of a second per minute is sufficient in the slave master clock so that the specific arrangement illustrated, by which the slave device gains a fraction of a second during the first part of each minute and is corrected to lose what has been gained at the end of each minute, is quite adequate.

The principal advantage in apparatus of the type herein described is in its simplicity, its adaptation to existing equipment without major redesign, and its smoothness of operation whereby the balance wheel of a spring clock is adjusted by magnetic force having no tendency to jam or damage the delicate escapement mechanism therewith associated.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claim.

What is claimed is:

In a secondary clock for use in a clock system wherein a spring-driven secondary clock is periodically brought into time agreement with a master clock by an electrical impulse transmitted by the master clock during the final portion of each of predetermined units of time, the combination of a spring-driven marine escapement mechanism in said secondary clock including a balance wheel constructed and arranged to oscillate about a normal rest position at a frequency greater than that necessary to measure accurate time as defined by the master clock and composed principally of a non-magnetic material, a magnetic slug insert mounted in the periphery of said balance wheel, a time shaft rotating under control of said escapement mechanism at a rate in excess of one revolution per said unit of time, electrical contacts, a cam on the said shaft constructed to close said electrical contacts during an initial portion of said unit of time as measured by the secondary clock, an electromagnet adjacent the periphery of said balance wheel and so located as to attract when energized the said slug and arrest the oscillation of said balance wheel at an angular position of the balance wheel other than said normal rest position, a circuit in which said contacts and said electromagnet are connected for receiving the

electrical impulse from the master clock to energize said electromagnet when said cam closes said electrical contacts during said initial portion and when said initial portion coincides with the transmission of the electrical impulse from the master clock.

RAYMOND H. BARROWS.
